FIG. 3

Fig. 4

To all whom it may concern:

Be it known that we, Noble Mayhill and Charles S. Brandt, citizens of the United States of America, residing, respectively, at Wichita, county of Sedgwick and State of Kansas, and Nevada, county of Wyandotte and State of Ohio, have invented a new, original, and ornamental Design for an Agricultural Harvester unit, of which the following is a specification, reference being had to the accompanying drawings, forming a part hereof.

Fig. 1 is a side elevation of an agricultural harvester unit showing our new design;

Fig. 2 is a rear elevation of the same;

Fig. 3 is a front elevation of the same, and

Fig. 4 is a side elevation of the same showing the side opposite that shown in Fig. 1.

We claim:

The ornamental design for an agricultural harvester unit, as shown.
